CLIP

Application filed June 29, 1928. Serial No. 289,125.

The present invention relates to improvements in clips, and refers more particularly to improvements in that type of clip used for suspending clothes or the like, comprising 5 a pair of spring tensioned legs provided with gripping jaws.

A clip of this character is very simple in construction comprising only two legs and a coil spring, opposite ends of which spring 10 surround the outer walls of the opposed legs. Such a clip is made to sell cheaply and it finds extensive use in tailoring shops, clothing stores and the like. It is also used, of course, for holding and suspending clothing in the 15 home, and is adapted for all of the uses for which a conventional clothes pin may be used. Due to its simple construction, the opposed legs frequently separate laterally of each other, becoming unlocked from registering 20 relation with the extremities of the spring and separating into two separate legs and a spring. The clip is then, of course, useless and because of its cheapness, users of this 25 type of clip will not spend the time necessary to reassemble the clip after it has become accidentally separated. As a consequence there is considerable wastage of clips.

It is an object of the present invention to provide a retainer guard or skirt for use with 30 the type of clip described above, so constructed as to prevent any accidental separation between the opposed legs of a clip while at the same time not adding materially to the cost of manufacture.

In its broad aspects the guard comprises 35 a metal skirt adapted to be slid over and enclose the two legs of the clip at a point practicable for force to be applied to separate the jaws of the opposed legs and at a point 40 where said skirt will not itself become accidentally disengaged, but will function in the most efficient manner for its intended purpose.

In a specific embodiment of the invention, 45 a pair of clips may be mounted on opposite sides of a hanger bar, the construction being such that the convolutions of the coil spring function as a screw thread, assisting in threading the clip with its retainer guard on the hanger bar and preventing the clip from

being removed from the hanger bar without the use of a force sufficient to distort same.

This specific embodiment comprises the provision of a retainer guard having an aperture in one wall and a closed opposite wall, 55 said aperture being disposed adjacent and in registering relation with the aperture formed by the convolutions of the coil spring. In combination with this retainer guard the ends of the hanger bar are bent to permit 60 the clip to be threaded on the hanger, the angle and pitch of the bend being such that after the end of the hanger passes through the last convolution of the coil spring, the 65 length of the bend is greater than the distance between adjacent convolutions or pitch of the coil spring.

In the operation of threading the bent end of the hanger bar through the convolutions of the coil spring, the coil spring being flexible will be slightly expanded while the bent end of the hanger bar is being threaded through the convolutions of the coil, but after it passes through the last convolution the latter contracts again to its normal position 75 and will thereafter prevent the bent end of the hanger bar from being threaded back. At the same time this construction does not thereafter interfere with the rotation of the 80 clip on the hanger bar.

The utility of the invention as well as other objects and advantages will be more apparent from the following description.

In the drawings, Fig. 1 is an elevational view of a hanger assembly illustrating a pair 85 of clips attached to opposite ends of the hanger bar thereof.

Fig. 2 is an enlarged sectional view illustrating the particular construction of the 90 clips.

Fig. 3 is a cross sectional view taken on line 3—3 of Fig. 2.

Fig. 4 is a cross sectional view of the retainer guard or skirt.

Referring more in detail to the drawings, 95 1 designates a hanger bar which may comprise round wire of proper length bent in the center to provide a loop 2 for the hook 3, the latter adapted to be suitably supported or suspended. A clip, designated as a whole at 100

4, is mounted on each end of the hanger. Each clip 4 comprises opposed legs 5 and 5' constructed in such a manner that in the normal position illustrated in Fig. 3 the lower inner faces of the legs will contact each other, as shown at 6, the upper inside surfaces of said legs being separated, as shown at 7. Each of the legs is provided on its inner surface with a groove or recess adapted to receive the coils 8 of a coil spring. The opposite ends of the spring project downwardly from the end of the last convolution of the coil 8, as shown at 9, being then bent at substantially right angles around the outer surfaces of each of the legs 5 and 5', which latter may be recessed, as shown at 10, to partially or totally countersink said projections 9'.

The construction is such, as stated heretofore, that in normal position the tension of the spring transmitted through the projections 9 and 9' will maintain the opposed meeting faces 6 in abutting or contacting relationship, providing a space 7. When it is desired to force the abutting faces 6 apart, pressure is applied adjacent the upper ends of said legs to decrease or entirely close the space 7, thus with the legs 5 and 5' acting as levers, and the coil 8 as the fulcrum, said pressure results in prying said meeting faces 6 away from each other. When pressure is released from the upper ends of the legs 5 and 5' the opposed meeting faces 6 will again come together due to the tension of the coil spring 8. Where an article is held between the two legs of the clip the meeting faces 6 will remain apart a distance equal to the thickness of the article being clipped or held thereby.

In the use of clips of this character the opposed legs 5 and 5' sometimes move laterally accidentally to disengage the projections 9', thus separating the two legs and the coil spring into three separate pieces, comprising two separate legs and a spring. Due to the cheapness with which these clips are manufactured and sold the user, as heretofore explained, does not take the time necessary to reassemble the separated elements, and this, of course, results in great wastage.

According to the present invention a combination retainer and guard 11 comprising a bent piece of some firm material, preferably metal, substantially rectangular in cross section, and hollow, is slid over both of the legs until it encloses and surrounds the coil spring 8. Where the clips are to be used individually the skirt or retainer 11 comprises a four-sided hollow structure of relatively thin material, the four sides of which may preferably be flat and not apertured. In this manner the element 11 will function solely as a retainer to prevent accidental separation between the two legs of the clip and the spring; the clip can be used indefinitely and will not become

accidentally disengaged. The retainer 11 will cost very little to construct and, therefore, does not add any appreciable cost to the clip. One wall of the retainer may be provided with means whereby it may lock with the coil spring to prevent the accidental disengagement of said retainer.

Where it is desired to use the clip and retainer of the present invention in combination with a hanger as illustrated, the retainer generally has one of its walls apertured, as shown at 12, the wall opposite thereto being non-apertured and provided with an outwardly bulging portion for a purpose to be hereinafter described. The ends of the hanger bar 1 are bent as illustrated at 14, the arrangement being such that the assembly comprising the clip and retainer, such as shown in Fig. 3, is engaged on the hanger as follows: The bent end 14 of the hanger bar is passed through the aperture 12 of the retainer and the clip rotated on said hanger whereby said bent end 14 will be threaded through the convolutions of the coil spring 8 until said bent end passes through the last convolution. The length of the bend being greater than the distance between adjacent convolutions of the coil spring, said bent end will be prevented from unthreading and the clip will merely rotate thereafter on the hanger, the closed end 13 functioning to limit excess end movement of the hanger bar and simultaneously covering and preventing the end of the hanger bar from tearing or scratching.

As before pointed out, the combination of clip and retainer is characterized by the fact that the elements comprising it will be prevented from accidental separation. This applies whether the clip is used alone or in combination with a hanger bar. When the clip is used in combination with a hanger bar, besides the advantage of being retained by the element 11, the clip will be permanently mounted on said hanger bar due to the bending of the end 14 and the threading of same through the convolutions of the coil spring as heretofore described. Finally, the closed ends 13 of the retainer guard 11 prevent the ends of the hanger bar 1 from tearing or scratching surfaces or articles with which they come in contact.

The device is highly efficient in use, extremely durable, and its many advantages are secured without a substantial increase of manufacturing cost over the types of clips of this character now in use.

We claim as our invention:

1. In combination, opposed legs a spring holding said legs in spring tensioned contacting relationship to form a clip, and a retainer enclosing and surrounding both legs and the spring to prevent unintended disassembly of the legs and spring.
2. In combination, opposed legs held in a

spring holding said legs in spring tensioned contacting relationship through the medium of a spring to form a clip, and a retainer enclosing and surrounding both legs and the 5 spring to prevent unintended disassembly of the legs and spring, said retainer comprising a firm material shaped to form an integral hollow structure.

3. In combination, opposed legs a spring 10 holding said legs in contacting relationship to form a clip, and a retainer enclosing and surrounding both legs and the spring to prevent unintended disassembly of the legs and spring, said spring comprising a coil, a 15 hanger bar formed of wire provided with a bent end, the latter being threaded through the convolutions of the coil spring.

4. In combination, opposed legs a spring holding said legs in contacting relationship 20 to form a clip, and a retainer enclosing and surrounding both legs and the spring to prevent unintended disassembly of the legs and spring, said spring comprising a coil, a hanger bar formed of wire provided with a 25 bent end, the latter being threaded through the convolutions of the coil spring, the pitch of the bend being greater than the distance between adjacent convolutions of the spring whereby the clip is prevented from disengagement from the hanger after being 30 threaded on the hanger.

5. In combination, opposed legs a spring holding said legs in contacting relationship to form a clip, and a retainer enclosing and 35 surrounding both legs and the spring to prevent unintended disassembly of the legs and spring, said spring comprising a coil, a hanger formed of wire provided with a bent end, the latter being threaded through the 40 convolutions of the coil spring, the pitch or angle of the bend being greater than the distance between adjacent convolutions of the spring whereby the clip is prevented from disengagement from the hanger after being 45 threaded on the hanger, said retainer having an aperture in one wall to permit the hanger to pass therethrough, and a non-apertured opposite wall provided with a bulged out portion whereby excess endwise movement 50 of said hanger bar is prevented while simultaneously the end of the hanger is enclosed.
